UNITED STATES PATENT OFFICE.

FRANKLIN SPAULDING, OF CHICAGO, ILLINOIS.

BUTTONHOLE-WORKING ATTACHMENT FOR SEWING-MACHINES.

1,080,729.

Specification of Letters Patent.

Patented Dec. 9, 1913.

Application filed April 5, 1913. Serial No. 759,055.

To all whom it may concern:

Be it known that I, FRANKLIN SPAULDING, a citizen of the United States, residing at Chicago, in the county of Cook and State of Illinois, have invented certain new and useful Improvements in Buttonhole-Working Attachments for Sewing-Machines, of which the following is a specification.

10 This invention relates to a device adapted to be attached to any of the well known domestic sewing machines and arranged to automatically work buttonholes of various sizes without any manipulation of the cloth by the operator.

The objects of the invention, generally stated, are to provide an attachment in which all of the functions necessary to produce a neat and secure buttonhole are accomplished by the fewest possible number of elements.

One of the objects of the invention, stated more particularly, is to provide improved means for translating the movement of the pivoted actuating lever to the friction clutch device.

Another object is to provide improved means for regulating or adjusting the length of the buttonhole to be formed.

20 A further object is to provide a simplified and more effective means for accelerating the movement of the driving wheel for the feeder plate for the purpose of maintaining the stitches uniform at the ends of the buttonhole and preventing the stitches from "piling up" at said ends.

Another object is to provide an improved clutch device which includes a driving clutch and a retaining or back-lash-preventing clutch.

The invention also relates to an improved means for oscillating the cloth feeder plate, for guiding said plate, and for switching said plate at the ends of the buttonhole.

45 The invention further contemplates the other details of construction which contribute to simplicity, as will be understood as the description proceeds.

In the accompanying drawings, Figure 1 is a top plan view of a buttonhole-working attachment embodying the features of my invention. Fig. 2 is a bottom plan view of the attachment complete. Fig. 3 is a bottom plan view with the cloth feeder plate and its retaining plate removed. Fig. 4 is a

side elevation taken from the top side of Fig. 1. Fig. 5 is a horizontal sectional detail view illustrating the means for accelerating the movement of the clutch wheel which actuates the cloth feeder plate. Fig. 6 is a fragmental detail plan view of said clutch wheel with the top plate thereof removed, said view illustrating the retaining or back-lash-preventing portion of the clutch.

The attachment in the preferred form, which I have herein shown, comprises a base plate 10 upon which are mounted the various mechanisms of the attachment. A standard 11 rises from one end of the base plate 10 and has at its upper end a clamp or yoke 12 adapted to embrace the presser-bar of the sewing machine after the presser-foot has been removed. A screw 13, threaded in the yoke 12, is adapted to rigidly secure the attachment to the presser-bar.

Two D-shaped plates 14 and 15 (Fig. 3) are pivoted by suitable pivot screws 16 and 17 to the underside of the base plate 10. Said plates have central openings 18 and 19 adapted to receive cams to be later described. The plates further have slots 20 and 21 therein, the side edges of which are under-cut to receive the edges of small blocks 22 and 23, respectively. Screws 24 and 25 are threaded in the blocks 22 and 23, the heads of said screws overlapping the edges of their slots and binding the blocks in any desired position therein.

A cloth feeder plate 28 is mounted beneath the plates 14 and 15, said cloth feeder plate having a longitudinal slot 29 into which the screws 24 and 25 project, the heads of said screws forming guides to direct the reciprocation of the feeder plate. In the present instance, this plate is provided with a central elongated opening 30, and the plate is held in place by means of a spring-retaining plate 31 overlapping the edges of the opening 30 and secured to the base plate 10 by means of the pivot screws 16 and 17. The spring plate 31 has a tongue 32 which passes through the opening 30 and bears against the oscillating cam, to be presently described, for the purpose of preventing movement of said cam through momentum. The plate 28 is mounted a cloth feeder proper. Beneath the forward end of the cloth feeder plate 28 is mounted a cloth feeder element proper 33, said cloth feeder having a plu-

rality of serrations 34 on its underside to engage the cloth and insure that the cloth will move with the feeder. A central slot 35 is formed in the feeder through which the needle of the sewing machine reciprocates in stitching the buttonhole.

Pivoted at 36 on a vertical lug 39, which may be bent upwardly from one edge of the base plate 10, is a lever 40 having at one end a notch 41 adapted to receive a screw commonly found on the needle bar of sewing machines. As the needle bar reciprocates up and down, the lever 40 is caused to oscillate on its pivot. A horizontal toothed plate 42 is rotatably mounted upon a vertical pivot shaft 43 and is provided with a segmental series of teeth 44 to mesh with teeth 45 formed in the lower edge of the lever 40. A ratchet wheel 46 is fixed upon the upper end 20 of the shaft 43 and is arranged to be engaged by a pawl 47 pivoted on the upper face of the toothed plate 42 and pressed by a spring 48 against said ratchet wheel. A five-sided oscillating cam 49 is fixed on the lower end of the pivot pin and fits within 25 the central opening 18 in the plate 14.

A clutch wheel 51 is rotatably mounted at the opposite end of the base plate 10, said wheel comprising a central shaft 52 and a plurality of disks 53 spaced apart and rigidly fixed to said shaft. Between the two lower disks is rotatably mounted a ring 54 having pivoted thereon a clutch dog 55, the nose of which is arranged to bind against 30 the edge of one of the disks 53, so that when the dog is swung in a counter-clockwise direction (Figs. 1 and 5) the clutch wheel, as a whole, will be given a partial rotation. A screw 56 is threaded in a nut 57 on the oscillating plate 42, and the end of said screw 35 is arranged to engage the clutch dog 55 so that as the plate 42 is oscillated, the said dog will be swung and the clutch wheel given a series of partial rotations. A coiled 40 spring 58, attached at one end to the clutch ring 54, and at its other end to a pin 59 on the base plate 10, is arranged to return the clutch ring to its normal position.

A second clutch ring 60 is rotatably 45 mounted between the two upper disks 53 and has associated therewith a dog 61, spring 62, and pin 63 in a similar relation to the clutch elements above described. The clutch dog 61 acts to permit free forward rotation of 50 the clutch wheel, but binds against one of the disks, so as to prevent rearward rotation or back-lash. The spring 62 tends to hold the clutch dog 61 in engagement with a pin 64 fixed in the base plate 10, whereby said 55 dog is maintained in engagement with its clutch disk.

The top plate 65 of the clutch wheel is removable from the wheel, being held in place by screws 66. Said plate has a radial slot 67 therein, the sides of which are under-

cut. In this slot is adjustably mounted a nut in which is threaded a thumb screw 69. A link 70 is mounted at one end upon the thumb screw and is pivotally attached at its other end to the adjacent end of the cloth feeder plate 28.

An arm 73 is pivoted at one end as at 74, upon the upper side of the base plate, said arm having an angular upwardly extending end 75 which lies behind the feeding clutch dog 55. The arm has a rounded projection 76 adapted to lie in contact with the peripheral edge of a cam plate 77 rigidly fixed to the central shaft 52 of the clutch wheel. The cam plate 77 has two arcuate portions and two flattened portions, as illustrated in dotted lines in Fig. 5. The angular end 75 of the arm 73 limits the backward movement of the clutch dog 55.

Upon the lower end of the shaft 52 of the clutch wheel is fixed a switch cam 79 (Fig. 3) which fits within the central opening in the pivoted plate 15, and acts to quickly switch the cloth feeder plate at the ends of the buttonhole.

The operation of the attachment is as follows: Reciprocation of the needle bar in the sewing machine oscillates the lever 40 and the segmental plate 42. The oscillating movement of the plate 42 is communicated to the pivot shaft 43 in the form of intermittent partial rotations through the medium of the pawl 47 and the ratchet wheel 46. As the cam 49, which is fixed to the lower end of the pivot pin 43 rotates, it engages the walls of the opening 18 in the plate 14 and oscillates said plate back and forth. This oscillation of the plate will be communicated to the cloth feeder plate 28 by the engagement of the screw 24 with the walls of the guide slot 29 in said feeder plate. Thus the cloth gripper 33 will move the cloth back and forth in a manner to cause zig-zag or buttonhole stitches to be formed therein. The length of oscillation of the cloth feeder plate and thus the length of each stitch may be controlled by adjusting the screw 24 longitudinally in its slot 20. In the oscillation of the toothed plate 42 the screw 53 will be carried into intermittent engagement with the feeding clutch dog 55 to rotate the clutch wheel 51 through intermittent partial rotations. Motion from the clutch wheel will be imparted to the cloth feeder plate 28 through the medium of the link 70 in the form of step-by-step advancing movements to carry the cloth past the needle of the sewing machine the entire length of the buttonhole.

The length of each step imparted to the cloth feeder plate, and therefore the distance between the stitches, may be controlled by adjusting the screw 56 in its seat. By turning the screw to advance its forward end, a greater swinging movement will be given to

the feeding dog 55 than when said screw is retracted. The arc of feeding movement of the dog 55 may thus be controlled.

The length of the buttonhole to be formed 5 may be governed at will by adjusting the thumb screw 69 radially in the slot 67. The nearer said screw is to the center of the clutch wheel, the shorter the buttonhole will be.

10 When the parts are in the position indicated in Fig. 1, wherein the thumb screw 69 is substantially mid-way of its travel longitudinally of the device, the cloth feeder plate will be given a maximum advancing movement with each partial rotation of the clutch wheel. When, however, said clutch wheel has rotated approximately ninety degrees farther than the position shown in Fig. 1, the dead-center will be reached, and the 15 travel of the cloth feeder plate for each partial rotation of the clutch wheel would be very slight unless means were provided to regulate the movements. The cam plate 77 at the bottom of the clutch wheel is so positioned with reference to the radial slot 67 20 that as said slot approaches either of the dead center positions in the rotation of the wheel, one of the flattened faces on said cam plate will move into engagement with the 25 projection 76 on the pivoted arm 73. This 30 will permit the angular end 75 of said arm to move toward the clutch wheel which will permit the feeding dog 55 to move back farther in its return movement. Thus the arc 35 through which the feeding dog swings is increased, and therefore the movement of the clutch wheel and of the cloth feeder plate is correspondingly increased. By this means I am enabled to maintain a substantially 40 uniform advancing movement of the cloth feeder plate, so that "piling up" of the stitches at the ends of the buttonhole is effectually prevented. The stitches will be uniform from end to end of the buttonhole. 45 It will be seen that this means is extremely simple and reliable, and is not apt to get out of order.

The switch cam 79, upon the lower end of the shaft 52 of the clutch wheel, is so positioned with relation to said clutch wheel 50 that as the cloth feeder plate 28 reaches the ends of its travel, said cam will engage the sides of the opening in the pivoted plate 15 and swing said plate. This movement will 55 be communicated to the cloth feeder plate through the engagement of the screw 25 with the guide slot 29 in said feeder plate. Thus, as the end of the buttonhole is reached, the cloth will be quickly switched 60 transversely of the length of the buttonhole, so that on the reverse movement of the feeder plate the needle will work the opposite side of the buttonhole. The extent of movement imparted to the feeder plate by 65 the switch cam may be regulated by adjust-

ing the screw 25 and its block 23 in the slot 21.

It will be seen that I have provided an attachment in which all of the functions, necessary to form a buttonhole, are provided by the fewest possible parts, and in every case the parts are such as may be easily and cheaply manufactured, and are so positioned as to be readily accessible for adjustment.

Substantially every part of the attachment may be stamped from sheet metal which conduces to cheapness in manufacture.

I claim as my invention:

1. In a buttonhole-working attachment, a cloth feeder plate, means for oscillating said plate including an oscillatory member, a screw threaded in said member, a rotary clutch wheel having a removable top plate, said top plate having a radial slot therein provided with undercut sides, a member mounted in said slot, a thumb screw mounted in said member, a link attached at one end to said screw and at its other end to said cloth feeder plate, and a clutch device including a dog adapted to engage said clutch wheel for imparting intermittent partial rotations thereto, said dog being adapted to be directly engaged and moved by the screw threaded in said oscillatory member.

2. A buttonhole-working attachment comprising a cloth feeder plate and means for advancing said plate including a rotary wheel and a link connecting said wheel to said plate, a cam fixed with relation to said wheel, a pivoted arm arranged to bear against said cam, a clutch device including a dog arranged to engage said wheel for rotating it, the backward and return movement of said dog being limited by said arm, and means for swinging said dog.

3. In a buttonhole-working attachment, a cloth feeder plate, a clutch wheel operatively connected thereto, an oscillatory device arranged to intermittently rotate said clutch wheel and means for limiting the return movement of said oscillatory device to control its arc of feeding movement, said means comprising a cam fixed with relation to said clutch wheel, and a member arranged to engage said cam and to limit said oscillatory device.

4. In a buttonhole-working attachment, a base plate, a cloth feeder plate slidably mounted thereon, a rotary clutch wheel operatively connected to said feeder plate, a clutch device including a dog adapted to engage said wheel and rotate it, means for moving said dog back and forth, means for limiting the return movement of said dog comprising a cam fixed with relation to said clutch wheel, and an arm pivoted to said base plate and adapted to bear against said cam, said arm having a portion against which said dog stops in its return movement.

- 5 In a buttonhole-working attachment, a base plate, an oscillatory plate pivoted to the underside of said base plate and having an opening therein, a cam fitting in said opening, means for driving said cam, a cloth feeder plate mounted for traveling movement beneath said oscillatory plate, said oscillatory plate and said feeder plate having longitudinal slots therein extending in 10 the same general direction, the slot in said oscillatory plate having undercut side walls, a block in the latter slot engaging said side walls, and a screw threaded in said block and adapted to secure said block in place, said 15 screw projecting into the slot in said feeder plate for communicating motion thereto.
6. In a buttonhole working attachment, a base plate, two oscillatory plates independently pivoted to the underside of said base plate and each having a central opening 20 therein, an oscillating cam fitting in one of said openings, a switch cam fitting in the other opening, a cloth feeder plate mounted for traveling movement beneath said oscillatory plates, said oscillatory plates and said 25 feeder plate having slots therein extending in the same general direction, a pair of studs each adjustably mounted in the slot in one of said oscillatory plates and projecting into the slot in the feeder plate, and 30 means for driving said switch cam and said oscillating cam.

In testimony whereof I affix my signature in the presence of two witnesses.

FRANKLIN SPAULDING.
